UNITED STATES PATENT OFFICE

157,025

SPOON OR OTHER ARTICLE OF FLATWARE

Milton B. Baker and David A. Baker, Hamden, Conn., assignors to The Majestic Silver Company, New Haven, Conn., a corporation of Connecticut

Application February 19, 1949, Serial No. 956

Term of patent 14 years

(Cl. D54—12)

To all whom it may concern:

Be it known that we, Milton B. Baker and David A. Baker, citizens of the United States, residing at Hamden, in the county of New Haven and State of Connecticut, have invented a new, original, and ornamental Design for a Spoon or Other Article of Flatware, of which the following is a specification, reference being had to the accompanying drawing, forming part thereof.

Fig. 1 is a face view of a spoon, showing our new design;

Fig. 2 is a rear view of the same; and

Fig. 3 is a sectional view on the line 3—3 of Fig. 1 on an enlarged scale.

We claim:

The ornamental design for a spoon or other article of flatware, substantially as shown.

MILTON B. BAKER.

DAVID A. BAKER.
